United States Patent Office

Des. 182,537
Patented Apr. 15, 1958

182,537

TABLE COVER

Richard S. Rader, White Plains, N. Y.

Application March 4, 1957, Serial No. 45,094

Term of patent 7 years

(Cl. D34—8)

Fig. 1

Fig. 2

The dominant features of the design reside in those portions shown in full lines in the drawing.

I claim:

The ornamental design for a table cover, as shown and described.
